Specification for Design.

Patented Sept. 20, 1921.

Application filed December 15, 1920. Serial No. 430,978. Term of patent 3½ years.

To all whom it may concern:

Be it known that we, JOSEPH I. PAPALE and GEORGE CAMPBELL, citizens of the United States, residing at San Francisco, in the county of San Francisco and State of California, have invented a new, original, and ornamental Design for Lamps, of which the following is a specification, reference being had to the accompanying drawing, forming part thereof.

Figure 1 is a front elevation, Fig. 2 is a perspective view, Fig. 3 is a rear elevation and Fig. 4 is a side elevation of a lamp showing our new design.

We claim:

The ornamental design for a lamp, as shown.

JOSEPH I. PAPALE.
GEO. CAMPBELL.
